(57) **CLAIM**

The ornamental design for a micro-flashlight docking station, as shown.

DESCRIPTION

FIG. 1 is a perspective view of a micro-flashlight docking station of the present invention;

FIG. 2 is a top view thereof;

FIG. 3 is a bottom view thereof;

FIG. 4 is a right side view thereof;

FIG. 5 is a left side view thereof;

FIG. 6 is a front view thereof; and,

FIG. 7 is a rear view thereof.

The broken line showing is for illustrative purposes only and forms no part of the claimed design.
